THE NORRIS PETERS CO., PHOTO-LITHO., WASHINGTON, D. C.

UNITED STATES PATENT OFFICE.

DAVID CARLAW, OF GLASGOW, COUNTY OF LANARK, SCOTLAND.

LETTER-PRESS PRINTING AND NUMBERING MACHINE.

SPECIFICATION forming part of Letters Patent No. 425,298, dated April 8, 1890.

Application filed October 16, 1888. Serial No. 288,281. (No model.) Patented in England August 22, 1887, No. 11,428; in France July 18, 1888, No. 191,878, and in Canada December 6, 1888, No. 30,344.

To all whom it may concern:

Be it known that I, DAVID CARLAW, residing in Glasgow, county of Lanark, Scotland, a subject of the Queen of Great Britain and Ireland, have invented Improvements in Letter-Press Printing and Numbering Machines, (for which I have obtained Letters Patent in Great Britain, No. 11,428, dated August 22, 1887; in France, No. 191,878, dated July 18, 1888, and in Canada, No. 30,344, dated December 6, 1888,) of which the following is a specification.

My said invention has reference to and comprises improvements in the construction or the general arrangement and combination of the parts or mechanical motions of a rotative or rotary letter-press printing and numbering machine for printing drapers' check-books, railway and steamboat tickets or labels, and like printing and numbering work from thin or thick paper or millboard or other prepared fabric for the purpose in the web or roll, and in which the short leaves, tickets, or parts have frequently to be printed on both sides and numbered in series or sequentially, and then perforated or cut at the required divisions or widths and lengths, all to be delivered from the machines numbered in continuous sets of one to fifty, or one to one hundred, or other series of numbers, according to the size of book or sets required to be put up together, and all printed and numbered by these improvements upon and formed out of a continuous traversing web while passing through this new rotating cylinder printing-machine.

In order to enable others skilled in the art to which my invention relates to understand the manner of performing or carrying the same into effect or practice, I have hereunto appended two explanatory sheets of drawings, in which the same reference-letters are used to indicate corresponding parts in all the figures where shown.

Figure 1 is a longitudinal side elevation of a rotary letter-press printing and numbering machine for printing the leaves of drapers' check-books or tickets in sequence on a web of paper, and constructed in accordance with and illustrating one general arrangement of my improvements and mode of carrying same into practice. Figs. 2 and 3 are transverse

sectional elevations as taken on the lines 1 1 and 2 2, respectively, of Fig. 1. Fig. 4 is a transverse section of the printing cylinder or roller B', carrying the numbering-disk mechanism D b b', also showing the upper part of the underplaten-roller C', which it acts against. Fig. 5 is a corresponding longitudinal sectional elevation of one end of the roller B', showing one set of the numbering-disk mechanism D b b' in edge view and the cam D⁴ secured to the side frame D for actuating same. Fig. 6 is an end view of this roller B' to show the cam D⁴ and its operating-lever D³, which actuate the numbering-disks b b'; and Fig. 7 is an end view of the numbering mechanism, showing the first or unit numbering-disk b and the actuating-pawl c c' and operating-levers c² D''' all as detached from the cylinder B'. Fig. 8 is a side and edge view of the numbering-disk b' and its ratchet-wheel b''' as slightly modified from that shown in Figs. 4 to 7, to print numbers from 1 to 100. Fig. 9 is a longitudinal sectional elevation of the delivery part of the machine shown in Fig. 1 to an enlarged scale, showing the cutting, punching, and paper-delivery rollers and bands and mechanism of the machine. Fig. 10 is a transverse sectional elevation showing the transverse cutting and punching rollers E' E² and mechanism detached, and Fig. 11 is a corresponding end view to Fig. 10, while Fig. 12 is a sectional end view, all these detail views Figs. 4 to 12 being shown to an enlarged scale from that shown in the general views, Figs. 1 to 3. Fig. 13 shows the sheets or leaves a' of a draper's check-book as printed, numbered, perforated, and delivered out of the web of paper a in this machine. Figs. 14 and 15 show end sectional views of a printing-roller B' and numbering-disk mechanism D b b' b² and actuating-pawl c c'' and levers c² and D''' as suitable for the three-disk arrangement for printing from 1 to 100, Fig. 16 showing the disks in side or end view. In these figures the direction of motion of the printing, perforating, and other cylinders or rollers and numbering-wheels is indicated by arrows, and the direction of motion of the web of paper through the machine is indicated by darts.

Referring to the general arrangement of the machine or mechanism shown in Figs. 1 to 3 and 9 to 13, the working mechanism is all carried on two main lower side frames A 5 A, secured together by cross stays or bars A', and preferably having a supplementary frame A², composed of two side frames secured together by cross-stays A'', carrying the bush-bearings and working-spindles of the printing and other rollers and mechanism, all bolted portably at A³ on the top of the lower frames A A at a proper height for the attendants to see the paper passing through the machine and to see the work as it is printed.

15 The web of paper a or other medium to be printed is mounted in a roll or roll form at a' on a spindle a'', carried in bearing-brackets at a² on the lower end frames A A. At the entering end of the machine a cord a³, weighted 20 at a', is passed over a pulley on the spindle a'' to serve as a tension for the web of paper. The web a is fed and drawn in over guide-rollers a⁵ and passed at a uniform rate over or between one, two, three, or more rotating 25 hollow printing-cylinders or tubular rollers B' B² B³, each carried on spindles B, and shifting bush-bearings B'' in the frames A², and pressure or platen or blanket rollers C' C², each carried on spindles C, working in sta- 30 tionary bush-bearings C'' in the frames A² A², working over, under, or against the paper a and each printing-roller B', B², or B³. Each platen-roller C' C² is covered with yielding or elastic tympan substance or blanket C³, se- 35 cured on the surface by a cross-bar and groove at C''', to give a good impression on the web of paper or fabric a from the type and numbering wheels b b' b², fitted within or on the said rotating hollow printing cylinders or roll- 40 ers B' to B³. The fabric a to be printed and numbered is passed straight and tangentially onto and between these printing and blanket rollers, driven through a chain of spur-wheels G on their spindles C at the back of the ma- 45 chine from the spindle C of the tympan-roller C' by a belt from any prime moving shaft passed over a first-motion fast and loose pulley d on the spindle C, as seen more partic- 50 ularly in Figs. 1 and 2; or the belt-pulleys might be on a counter first-motion shaft below the shaft C and geared to it by spur-wheels.

The printing cylinders or rollers B' B² B³ are preferably made of a hollow tubular form with removable ends and journal-shafts B 55 secured in them, as seen particularly in Fig. 2, which rotate in movable bush-bearings B'', preferably fitted with yielding springs and tightening-screws B''' in the side frames A², as before mentioned, and they are all driven 60 by their said gearing at one uniform circumferential speed and draw through the paper a between them over its guide-rollers a⁵. The circumference of the printing-rollers B', B², and B³, on which the type and numbering 65 mechanism are mounted, is as near as possible the length of each complete ticket, so as to print a ticket a^x at each revolution, as shown

in Fig. 13; but it might be made of a size to print a number of tickets, as two, three, or four, in the circumference or revolution. 70

The fabric a is printed and numerically numbered in this machine to suit for three widths or continuous strips or sheets of tickets in the width of the web of fabric to be printed, each set being printed with the same 75 number in succession from 1 to 50 or 1 to 100, thus delivering three sets of sheets of these numbers in a regular successive manner, similar to the two sheets shown in Fig. 13, which shows the fiftieth sheet as printed; but the 80 machine and cylinders might be made to take in a greater or less number of tickets or sheets in the width, as desired. After passing through between said platen and printing-rollers and numbering-rollers, the web is made to pass 85 through between transverse perforating-cylinders E' E² on spindle E, carried in bush-bearings E'' in the side frames A² A², as seen particularly in Fig. 1 and in Figs. 9 to 11 on enlarged scales. These cylinders E' E² are 90 preferably made in the form of disks or pulleys secured on their shafts E at some distance apart, their spindles E being actuated by a continuation of the train of spur-wheels G at the back of the machine. The under 95 roller E² is fitted with three long transverse serrated blades e e', working in radial grooves in their pulleys E², each blade e being actuated by a radial moving bow-arm e'' at its ends, working in guides E³, and actuated by 100 adjusting cam-rollers e''', carried in brackets E⁴, bolted to each side frame A A of the machine under the roller E², all so as to cause each serrated blade e e' to pass up into a fine slit in each of the corresponding three long 105 transverse wood bars e² as they come round in the roller E', in which they are divided and securely fitted to exactly meet and receive the blades e e' as they come round. Each blade e e' is gripped between plates and 110 drawn into its recess by spiral springs e³, except when pushed out by their actuating-arms and cam-rollers e'' e''', all as seen particularly in Figs. 9 to 12.

One of the serrated bars e is made with 115 fine teeth, so that at each revolution it really cuts the paper through right across the whole web and set of sheets a^x of the paper at the ends d^x, (seen in Fig. 13,) and the other two serrated blades at e' each time they come 120 round perforate the paper and sheets, as indicated at e^x in Fig. 15.

To give a certain amount of grip on each side of the paper on the wood bars e² while it is being cut by the blades, the slit metal block or blocks e⁴ are preferably fitted with spiral springs e⁵, to be slightly pressed out beyond the surface of their rollers B², as seen particularly in Fig. 12. The paper a, after being so perforated transversely, is conducted 130 over a set of fingers f, mounted over and between the rollers E² on a transverse oscillating spindle f' and carried between two conducting sets of bands or tapes F' F², passed

over-rollers and spindles F, mounted on the delivery side of the rollers E' E² in brackets f², secured to the side frames A² A². These bands F' F² are carried over conducting and driving rollers and spindles F'' F³ near the delivery end of the machine, as seen particularly in Figs. 3 and 9. The paper between these bands F' F² is carried, so as to be cut longitudinally, as indicated at g^x in Fig. 13, by four sets or pairs of cutting-disks g' g², mounted, respectively, on the spindles g' g², carried in bearings in the side frames A² A² and actuated by a train of spur-wheels g³ on studs secured on the inside of the front frame A, as shown particularly in Fig. 3, and actuated by a spur-wheel g⁴ on the spindle E of the perforating-roller E², as seen in Fig. 2 and as all dotted in, in Figs. 1 and 9. The spindle E of this roller E² also, by a pair of small bevel-wheels h at its back end, actuates an angled shaft H, (carried in bearing-brackets H', secured to the back frame A²), which, by bevel-wheels h', actuates the spindle I of a set of rollers I' and set of bands i, passed over a driving-roller and spindle F''' above it. Both spindles I and F''' of these bands i are carried in bearings in the upper part of the frames A² A². The latter spindle by small spur-wheels j actuates the upper spindle and rollers F³ of the endless band F², which carries the paper a, with the bands F', so as to deliver them onto the set of bands i, where they are wound in sets of four over each other, while a fifth is delivered simultaneously as it is fed forward, as will hereinafter be explained. V-shaped guide-fingers f³ conduct the paper over the roller F³ onto the bands i, and other two sets of endless bands k and l, passed over pulleys k' and l', conduct the printed and cut sheets round the bands i and the downward delivery part of the bands F', passed over the delivery-rollers F⁴ and l² of the bands f and l, the spindles of which are driven by a train of spur-wheels l³ (shown dotted in, in Fig. 9) from a spur-wheel on the spindle I of the rollers I'. These rollers l² and F⁴ and bands F' and l deliver the sheets between two endless bands k and k', passed round rollers K and K', mounted on spindles in a delivery rocking frame K², oscillated by rods k'' and levers k² k³, by a five-ratchet-toothed cam k⁴, secured on the same spindle H² as a five-notched circular disk-cam k⁵, mounted on the inside of the back frame A², and actuated by a screw-wheel H'' from a screw H''', mounted on the angled shaft H outside the back frame A², so as to rotate these cams k⁴ and k⁵ once for every five revolutions of the shaft H and perforating-rollers E' E², all as seen particularly in Figs. 3 and 9.

60 The cam k⁴, for oscillating the delivery rocking frame K, may be mounted on a separate spindle from the cam k⁵, and actuated to make only one revolution for five of the printing-cylinders B' B² B³, and have only one tooth or rise in the circumference for actuating the lever k³ of the rocking delivery-frame K.

A double-armed lever m is so mounted on a short spindle m' that an anti-friction roller m'' on its lower arms works on the periphery 70 of the notched circular cam k⁵, and through a rod m², connected at its near end to the upper arm of the lever m and spindle m' and at the other end to a rocking shaft, on which are mounted two sets of the paper-guiding 75 fingers m³ m³', all so that as the roller m'' is passing over the plain part of the cam k⁵ it causes five sets of the paper sheets as printed to be guided successively between the bands i and k over each other onto the endless bands 80 i, and as each notch comes round in the cam k⁵ the roller m'' falls into it and shifts the guiding-fingers m³ outward, as dotted in, in Fig. 9, so as to deliver the whole five sheets laid over each other on the bands i as they 85 come round between the band F' and the bands l and deliver them in a set through the rollers F⁴ and l² in between the bands k k' of the delivery oscillating frame K², which at the same instant is, by the raised part of the cam 90 k⁴, caused to assume the dotted position shown in Figs. 1 and 9 by its moving cam k⁴ and levers k² k³ to deliver each five sheets at once, all collated or arranged in sequence over each other onto the angled trough part L' of the 95 receiving sliding or moving table L, mounted by slides or otherwise on brackets L² on the delivery end of the machine and side frame A A. As each set of sequentially-numbered five sheets a^x are so delivered very quickly 100 into one trough L', the attendant shifts the frame L laterally in its slide-brackets L² to one side, so that while removing one five sets delivered the next five sets are being delivered into a trough L' at the opposite side of 105 the table L, as shown in Fig. 1, when the table L can then be shifted in the reverse direction to remove the sets in succession alternately and successively as they are delivered from opposite sides of the table L, thus enabling 110 the sheets or tickets a^x to be removed in sets while they are being printed at a very high speed, as shown more particularly in Fig. 1.

The paper a to be numbered and printed is passed, first, in this example and arrangement of the mechanism and numbering and printing rollers B' B² B³, with the back of the paper onto the first numbering-roller B', and then round over and under the blanket-roller C', so as to get the first and second sets of 115 successive numbers of 1 to 50 or 1 to 100 printed on the back of the paper, as shown dotted in at the lower part of Fig. 13, by sets of the numbering mechanism shown fitted within small cases or frames D, (shown in 120 section within the roller B' in Fig. 2 and in detail in Figs. 4 and 5,) and so that the numbering-disks b b' project through segmental recesses at D' in the roller B', so as to print the paper passing through between it and the 125 tympan-roller C', the roller B² being formed and fitted substantially the same as B', only having the numbering mechanism placed or divided so as to print the second set of num-

bers on the back in the proper place, as indicated in Fig. 13, with a transverse perforated division e^x between these numbers, so as to leave the first set of numbers stitched in the book and be able to tear off the upper two parts of the sheets a^x with the numbers on it for use. The paper passes from the first tympan-roller C^2 with the face or front of the paper upward, with the third numbering and letter-press printing-roller B^3 over it, so as to print the third set of numbers and the letter-press and lines of money-columns in the upper parts of the sheets on this front or upper side of the paper, as seen particularly in Figs. 9 and 13.

The numbering mechanism $D b b'$, as also the segmental stereotype-plate B^4 , is shown in the section of the roller B^3 in Fig. 9.

The continuous printing of the letter-press is effected by forming the segmental stereotype or electrotyped plate B^4 of the letter-press required and securing this on the outer surface of the tubular printing-cylinder B^3 within a groove in the proper circumferential position to print this on each sheet or ticket or part of the sheet of each strip of tickets, as indicated in the upper part of Fig. 13, so that as many plates would be secured on the circumference along the hollow cylinder as there are sets or strips of tickets to be printed by it—that is, three in this case, two of which are shown in Fig. 13.

The numbering disks or wheels b , b' , and b^2 for printing from 1 to 50 or 1 to 100 are all made of the same diameter and divided specially in equal divisions different in each disk, having projecting printing-teeth at these divisions, with the numbers cut on their projecting printing-faces, or the absence of printing-teeth at these divisions where numbers are not to be printed. Each disk b , b' , or b^2 has an actuating ratchet-wheel b'' , b''' , or b^4 secured on its one side, with a tooth corresponding to each division, and a spring-lever moving ratchet-pawl $c c' c''$ mounted at one side of the plate-frame D on the free end of a spring-actuating lever c^2 , fulcrumed on a stud c^3 at the other, so as to actuate each ratchet-wheel and bring the particular tooth of each disk in one radial line at the part where they print the numbers on the fabric through a narrow recess D' , formed from the inside of the tubular printing-cylinders B' B^2 B^3 , rounded off inside, so as to allow these printing-wheels to turn inside clear of the tubular case of the cylinder and allow the numbers on the disks to project and print through the narrow recess at D' in the printing-cylinder as it comes on the paper between it and the platen or pressure roller C' and be inked after the disks have passed round from the paper and shifted to the new numbering position just before they come up to the paper again to print the next number, by an arrangement of inking roller or rollers or equivalent inking-surface brought into action against the printing-surface of the numbers as they come

round, all as will hereinafter be described. The ratchet-wheels b'' , b''' , or b^4 have also spring-lever ratchet-detents c''' mounted on the opposite side of the ratchet-wheels to their actuating-pawls $c c' c''$, so as to hold and retain the ratchet-wheels and their numbering-printing disks in the said printing position to which they are set by their moving pawls. 75

Referring to the detail views, Figs. 4 to 7, the numbering of each strip of tickets in continuous sets of fifty is by these improvements effected by a novel construction and arrangement of two small numbering narrow disks 80 or wheels b b' and their ratchet-wheels b'' , b''' and respective actuating-pawls c c' and fittings mounted in a light double plate-frame D , secured and fitted within each hollow printing-cylinder B' B^2 B^3 . The first numbering-disk b on the left-hand side of figures, for printing the units on the right-hand side, as shown in Fig. 13, is divided into ten printing divisions and projections or teeth, having engraved or cut printing-numbers 1 to 9 and 90 a cipher on the tenth on the edge surface of the tooth, as indicated in Fig. 7, with its ratchet-wheel b'' behind it, with a corresponding number of teeth, while the second disk b' , which prints the tens on the left of the former, (seen to the right in Fig. 5,) is divided into twelve divisions and with twelve teeth on its ratchet-wheel b' , five divisions in each half of the circumference of the disk, with a blank in the center between each five divisions, and its actuating-pawl c' turns this disk b' one division for each revolution of the unit-disk b , as indicated in Fig. 4. The actuating-pawls c c' of the respective ratchet-wheels b'' , b''' and disks b b' are both fulcrumed on one 105 stud-pin in the outer end of a short spring-lever c^2 , oscillating on a center c^3 out from the ratchet-wheels, and so that this lever c^2 can be oscillated, so as to turn the ratchet-wheels, by a light spindle D^2 , passing across through the cylinders B' B^2 B^3 , with a short actuating-wiper D''' on it to actuate each pawl-lever c^2 , and a lever D^4 , with an anti-friction roller or other equivalent on the outer end of this spindle D^2 , working in or over a cam D^4 , secured to the inside of the front frame A^2 , as seen particularly in Figs. 5 and 6, all so as to actuate the pawl-levers c at each revolution of the numbering printing-rollers B' B^2 B^3 just after the numbering-disks b b' have printed the web of paper, the spring c^5 bringing back the pawl-lever c^2 after each action to its normal position against a fixed stop ready for the next action of shifting the pawls and the numbering-disks, and the action of the mechanism for giving the numbers 1 to 50 with these disks is as follows: Each revolution of a numbering printing-roller B' , B^2 , or B^3 , through the cam D^4 and first ratchet pawl c and ratchet-wheel b'' , turns the first or unit disk b one number 110 at each action and revolution, and at each revolution of the unit-disk, as the cipher comes round and prints, the pawl c falls into a deeper ratchet-tooth on its wheel b'' of this 115 120 125 130 135

disk b , which allows the pawl c' of the second disk b' to fall into one tooth of its ratchet-wheel b''' , and so turns this wheel of the tens one division each revolution of the units-wheel as it brings the cipher into the printing position and does each revolution for five times—that is, printing 10, 20, 30, 40, 50—in which latter position—that is, after the 50 is printed, as shown in Figs. 4 and 13, and 5 the 1 is again to be brought into position for printing the first unit of the set—the second pawl c' takes into a raised or deep tooth on its ratchet-wheel b''' and brings the blank space into the printing position at the same 10 time as the one on the unit-printing wheel was brought into printing position by its ratchet-wheel b'' , there being a raised tooth for every blank space and half-revolution of the left-hand printing-disk b' printing the 15 tens, (shown on the right in Fig. 5,) and this blank space remains until a complete revolution of the unit-wheel takes place again, when the ratchet-pawl c of the unit-wheel b falls into its deep tooth and brings round the 20 printing-disk b' one tooth to print the tens successively, as before explained, from 1 up to 50, each time the cipher comes up on the units-wheel. A light spring c^x on the second pawl c' always brings it against a stop c^y on 25 the pawl c of the first wheel b , which keeps it out of gear with its ratchet-wheel b'' , except when the first pawl falls into the deep tooth before referred to at each time the ninth unit comes round, so that it shifts only one 30 division each revolution of the unit-wheel and is free to rise over its high ratchet-tooth each time the fifth division of its disk printing the tens comes round to bring the blank space into the printing position. In this way 35 the mechanism goes on printing tickets in continuous series of 1 to 50. The stops on the pawls c c' are shown in the form of lateral pins at c^y in Figs. 4 and 7; or otherwise, by a slight improvement, this two-numbering- 40 wheel arrangement may be made to print from 1 to 100 of the numbers in succession, as shown in side and edge view in Fig. 8, by forming the disk b' , for printing the tens, with only one blank space in its twelve divisions, 45 and numbers 1 to 5 in the succeeding five divisions, and a repeat of the five on the space opposite the blank division, with the figures 6 to 9 and a cipher on the following five divisions, and with a lateral tooth having a 50 figure 1 on it on the side of the tooth with this cipher, so as to print 10, and with the cipher on the units-wheel give the 100 when this tooth comes round, and having a high tooth on its ratchet-wheel b''' to bring the 55 blank spaces into printing position and another exactly opposite when bringing the second five into printing position each time the ratchet-pawl c of the unit-wheel falls into its deep notch to turn the numbering-wheel b' to bring its figure 1 into printing position. The arrows on these figures 4 to 8 show the 60 direction of motion of the cylinders, and the

printing-disks have their figures correspondingly cut or ranged to turn in this direction, although it is not necessary that the numbering-disks should turn in the same direction as the cylinders, as the levers D''' D^3 and cam D^4 might be arranged to turn these in either direction by the motion of the rollers. 70

Referring to the three-disk-numbering arrangement (shown in Figs. 14 to 16 on Sheet 2) for printing the tickets continuously in sets of from 1 to 100, the first numbering unit-disk b and its ratchet-wheel b'' and pawl c are fitted and act all substantially the same 80 as in the arrangement for printing in series from 1 to 50, or 1 to 100, described in reference to Figs. 4 to 8 on Sheet 1; but the second or tens-numbering disk b' is divided into eleven equal divisions, with ten projecting 85 teeth, numbered 1 to 9, and a cipher in the tenth tooth, and with a blank space in the eleventh division, and one raised or deep tooth on its ratchet-wheel b''' for bringing this blank space into printing position after it 90 has printed the cipher, as numbered and seen particularly in Fig. 14, and the third disk b^2 , for printing the hundred, is divided into ten divisions, with alternate printing projecting teeth and blanks, with a figure 1 on each projection, and fitted with a ratchet-wheel b^3 and spring-pawl c'' , with a high or deep tooth on every alternate division of its ratchet-wheel b^3 for bringing blank spaces into printing position. Thus the action is as follows: The 95 second and the third wheels b' b^2 remain with their blank spaces in the printing position while the unit-wheel b is turned to bring its printing-teeth 1 to 9 into action at each revolution of the printing-cylinders B' B^2 B^3 . 100 In this position the pawl c falls into the deep tooth and causes the pawl c' of the second wheel b' to bring its figure 1 into printing position as the cipher on the unit disk b comes into printing position. When the unit-wheel 105 has made a complete revolution and brought the cipher again into position, it brings the number 2 of the second wheel b' into printing position, and so on each revolution of the unit-wheel until the first and second wheels print 110 99, when by the next movement of the pawls c c' both ratchet-wheels b'' b''' and disks b b' are turned to bring the two ciphers of the first and second disks of the units and tens into 115 printing position, and the pawl c' of the second disk b' , falling into a deep-cut tooth on its ratchet-wheel, allows the pawl c'' of the third ratchet-wheel b^3 to take into one of its low teeth and turn it one division to bring one of its projecting teeth into position to print 1, 120 making the 100, and thus prints the 100 successively on the web of fabric each time the second disk b' makes one revolution. The 125 next movement of the unit ratchet-wheel b'' , which brings the 1 into printing position for 130 the new series, causes the pawls c c'' of the ratchet-wheels b''' b^3 of the second and third printing-disks b' b^2 to take on to their raised projecting teeth and turn the printing-disks

$b' b^2$ to their blank positions, where they would stand until the cipher of the first unit-wheel b comes into printing position, so that the deep tooth in the ratchet-wheel b'' of its disk 5 would bring number 1 into position again on the second disk, and so on until 99 was printed again and the ciphers on the first and second printing-disks $b' b'$ were again brought into printing position with one of the projecting 10 teeth of the third disk in line, so as to print the 100 again successively and continuously on the web of paper, as described in reference to the first 100. The arrows in Figs. 14 to 16 also show the direction of motion of the 15 cylinders and printing-disks corresponding to Figs. 4 to 8. Two, three, four, or more of these arrangements of numbering-disks $b' b' b^2$ and their narrow plate-frames D are secured within the hollow cylinders $B' B^2 B^3$, as seen particularly in Fig. 2, each within its recess D' through the cylinder, in the positions and according to the number of strips of tickets to be printed in the width of the web passing between the printing-rollers $B' B^2 B^3$ and the 25 platen pressing-rollers $C' C^2$.

The projecting surfaces of the numbering printing-disks $b' b' b^2$, projecting through the slits D' in the tubular printing-cylinders $B' B^2$, are inked just before they come round to 30 print on the paper a over the entering end of the machine by an automatic inking-roller n , carried in journal-bearings over inking-troughs n' , turned intermittently by an arrangement of ratchet-wheel and levers n^2 and 35 served from this roller intermittently by a pilot-roller n'' , carried over the trough n' on side levers and a rocking shaft n^3 , actuated by cams n^4 on a light horizontal shaft N , carried on brackets on the front side frame A^2 of the 40 machine and actuated by a screw-wheel and screw N' on one of the horizontal spindles C of the blanket-cylinder C' or other cylinder of the machine. This pilot-roller n'' serves the ink to the rotating distributing-roller 45 O , which in turn serves it onto the narrow inking-rollers $O' O^2$, which work over the grooves in the cylinders $B' B^2$ at D' , where the numbering-disks project to be inked. The distributing-roller O is actuated by a train of 50 spur-wheels (dotted in at O'') from a wheel on the spindle B of the upper printing-cylinder B' . An upper small distributing-roller O^3 is moved laterally over the large distributing-roller O by an arrangement of bell-cranks o 55 and eccentric on the shaft N and rod o^2 . The segmental stereotyped plate B^4 and numbering-disks $b' b^2$, mounted on the last printing-cylinder b^3 , are also inked by a similar arrangement of inking and pilot serving rollers $n n''$, 60 with trough n' and large distributing-roller O , over the back part of the machine, so far substantially the same and actuated by a front horizontal shaft N in an equivalent manner to that described for inking the numbering-disks $b' b'$ of the front printing-rollers $B' B^2$; but a second large distributing-roller O^4 65 is here employed, with two pairs of small lat-

eral distributing-cylinders O^3 working over these large distributing-rollers $O O^4$, reciprocated by horizontal-beam levers $o' o'$, carrying their journal-bearings and vertical bell-crank lever o from the reciprocating rod of an eccentric o^2 on the shaft N . The second large distributing-roller O^4 serves the ink onto the small service-roller O' , which directly inks 70 the surface of the stereotype B^4 and numbering-disks $b' b'$ of the cylinder B^3 , all as seen particularly in Figs. 1, 2, and 9, the distributing-rollers $O O^4$ being rotated by a train of spur-wheels (dotted in at O'') from a wheel on 75 the spindle B of the cylinder B^3 at the back of the machine.

A hand-lever P , convenient for the attendant, is fitted at the back delivery end of the machine, with a rod p leading back to a bell-crank lever p' for working a belt-fork sliding bar arrangement carried in brackets p^2 near the belt-pulleys $d d'$, so as to shift the belt d' from the slack to the tight pulley, or vice versa, instantaneously, according as the machine is delivering the sheets in a proper printed perforated and collated manner.

What I claim is—

1. In a machine for printing and numbering sheets or tickets from webs of paper or other fabric, the combination, with rotary tubular cylinders having openings in their peripheries, of sets of disks with numbering teeth or projections mounted within the cylinders, and mechanism also within the cylinders to rotate the disks, whereby sets of different numbers are successively brought to the openings in the cylinders, substantially as and for the purpose set forth.

2. In a machine for printing and numbering sheets or tickets from webs of paper or other fabric, the combination, with a rotary cylinder, of numbering mechanism consisting of two or more numbering-disks with ratchet-wheels and pawls within the said cylinder, the said disks having numbers to print from 1 to 50 or 1 to 100, consecutively and continuously, substantially as set forth.

3. In a machine for printing and numbering sheets or tickets from webs of paper or other fabric, the combination, with rotary tubular printing-cylinders having openings in their peripheries, of sets of numbering-disks mounted within the cylinders, ratchet-wheels and pawls to actuate the disks, and a single spindle to actuate the pawls to bring the numbers consecutively before the openings in the cylinders, substantially as described.

4. In a machine for printing and numbering sheets or tickets from webs of paper or other fabric, the combination of rotating tubular printing-cylinders having openings in their peripheries with sets of numbering-disks and means for actuating said disks, mounted within the cylinders, and segmental printing-plates secured to the outer surfaces of the cylinders, whereby sheets or tickets are printed and numbered consecutively at the

5. In a machine for printing and numbering sheets or tickets from webs of paper or other fabric, the combination, with a rotary cylinder, of numbering mechanism consisting of two or more numbering-disks with ratchet-wheels and pawls within the said cylinder, the said disks having numbers to print from 1 to 50 or 1 to 100, consecutively and continuously, substantially as set forth.

same time, substantially as and for the purpose set forth.

5. In a machine for printing and numbering sheets or tickets from webs of paper or other fabric, the combination of a rotating tubular printing-cylinder having openings in its periphery with two or more sets of numbering-disks and actuating mechanism for the disks mounted within the cylinder, whereby two or more corresponding strips of paper for sheets or tickets may be numbered at the same time, substantially as described.

6. The combination, with a printing-machine, of a perforating device consisting of two rollers, transverse serrated blades movable

radially in one roller and corresponding slits in the other, adjustable cam-rollers and bow arms having one end attached to the blades and the other end adapted to pass over the cam-rollers, substantially as and for the purpose set forth. 20

In testimony whereof I have signed my name to this specification in the presence of two subscribing witnesses.

DAVID CARLAW.
